METHOD OF AND APPARATUS FOR UPSETTING HOLLOW RIVETS

George W. Deshon, Paris, and Paul Emile Marie Amann, Vitry, France, assignors to United Shoe Machinery Corporation, Borough of Flemington, N. J., a corporation of New Jersey

Application May 3, 1939, Serial No. 271,556
In Great Britain May 2, 1938

17 Claims. (Cl. 218—19)

This invention relates to riveting and is particularly concerned with the problem of upsetting hollow rivets in situations where access to one end of a rivet is possible only through the rivet itself, as in closed hollow structures such as a container fabricated from sheet metal or the fuselage of an airplane so designed that a workman could not operate inside the shell thereof. Riveting under these conditions has been accomplished heretofore with riveting mandrels of the "break-head" type which requires a new mandrel for each rivet so upset and clenched.

To avoid the waste and nuisance incidental to the use of break-head mandrels the present invention provides improvements in riveting methods and riveting apparatus, in consequence of which a riveting mandrel may be used to upset a large number of hollow rivets through or into which it may be inserted to place it in an operative position.

A feature of the invention is embodied in a riveting mandrel of novel construction which, by the exercise of the force of leverage, is capable of acting against both ends of a rivet simultaneously in addition to acting against the internal surface of the hollow shank thereof. We conceive it to be a new principle in this art so to utilize the force of leverage of a single instrumentality to upset both ends of a hollow rivet simultaneously and at the same time to expand, if conditions permit, the intermediate shank portion of the rivet.

Another novel feature of the invention is embodied in a riveting apparatus including such a mandrel and mechanism so organized as to utilize centrifugal force to supply the leverage above mentioned and a gradually increasing angle of displacement of the mandrel as the rivet responds to the forces acting upon it.

The features above mentioned and others are hereinafter described and claimed and are illustrated in the accompanying drawings, in which

Fig. 1 is a sectional view of a hollow rivet closed at one end and extending through two lapped metal plates about to be connected by upsetting the rivet with the mandrel located therein and occupying its initial position;

Fig. 2 is a similar view representing an intermediate stage of upsetting the rivet;

Fig. 3 represents the same rivet in its final stage, both ends thereof having been upset by the mandrel to secure the metal plates tightly one against the other;

Figs. 4 and 5 are sectional views of another type of rivet before and after being upset and

clenched by a mandrel of the type shown in Fig. 5;

Fig. 6 is a view corresponding to Fig. 5 except that the mandrel has been removed and the cavity in the rivet is filled with a plug and retaining material;

Figs. 7, 8, 9 and 10 are sectional views representing successive stages of securing two rivets one within the other to provide a reenforced connection of the metal plates through which the rivets extend;

Fig. 11 is a sectional view of a power-driven riveting machine suitable for performing the riveting operations herein illustrated and described;

Figs. 12 is a cross-section of the machine partly in the plane of line XII—XII of Fig. 11 and partly in a lower plane; and

Fig. 13 is a sectional view of the structure intersected by line XIII—XIII of Fig. 11.

Referring to the assembly of work represented in Figs. 1, 2 and 3, the problem is to secure together two plates 10 and 11 of sheet metal with hollow rivets of the type shown. Assuming that the elements 10 and 11 are lapped margins of plates to be fabricated to construct a shell accessible only from the outside, they are held in the desired relation while rivet-receiving holes are bored through both at once. The rivet shown in Figs. 1, 2 and 3 is made of comparatively soft ductile metal such as aluminum, the end 12 thereof being closed and the opposite end being open and having a radially projecting surface flange 13 to be seated against the outer plate 10. The shank portion 14 of the rivet is cylindrical.

The mandrel best suited to upset and clench a rivet of this type comprises a cylindrical shank 15, an annular upsetting shoulder 16, an upsetting head 17 and a tapered neck 18 connecting the shoulder and the head, the smaller end of the neck adjoining the head and the larger end of the neck adjoining the shoulder. Preferably the largest portion of the neck is the middle zone 19 of a sphere (defined by broken lines in Fig. 1) the diameter of which is preferably commensurate with that of the head 17, to the end that this spherical zone will have a circular bearing on the internal surface of the rivet and provide a suitable fulcrum on which the mandrel may rock under the force of leverage to displace the head 17 radially away from the axis of the rivet as the upsetting operation progresses.

When the flange 13 of the rivet is seated against the outer plate 10, the closed end 12 of the rivet projects a considerable distance beyond

15

20

25

30

35

55

the inner surface of the inner plate 11, and when the mandrel is correctly located in the rivet, the center of the spherical zone 19 preferably lies approximately in the plane of the contacting surfaces 5 of the plate 10 and the flange 13. Moreover, the head 17 then projects beyond the inner face of the plate 11 and nearly but not quite to the closed end 12 of the rivet. Now, with the mandrel standing initially in coaxial relation to 10 the rivet, the force of leverage applied to the outer end of the mandrel will tilt the latter about the center of the spherical zone 19, thereby displacing the head 17 in one direction away from the axis of the rivet and displacing the upsetting 15 shoulder 16 in the opposite direction. It is to be assumed, of course, that the hole bored in the plates 10 and 11 to receive the rivet will be only large enough for that purpose and that the rivet itself will not be tipped by the force of leverage 20 applied to the mandrel.

The riveting operation utilizes not only the force of leverage above mentioned but also utilizes movement of the mandrel about the axis 20 of the rivet with the result that the mandrel executes a 25 gyroscopic motion which produces a spinning action of the head 17 against the inner end of the rivet and a corresponding spinning action of the shoulder 16 against the outer end thereof. Thus, the head 17 and the shoulder 16 simultaneously upset 30 two diametrically opposite segments of the rivet, one at each end thereof, and these segments are extended circumferentially with a common direction of progression about the axis of the rivet in consequence of the gyroscopic motion of the mandrel. During the early stages of upsetting (see 35 Fig. 2), the annular shoulder 16 is not effective to upset the open end of the rivet because it is slightly smaller than the latter but the head 17 has no corresponding clearance and therefore 40 takes effect immediately to impart a bulbous formation to the closed end of the rivet, thereby initiating the clinching effect of the rivet to maintain the flange 13 firmly against the outer plate 10.

When the upsetting has progressed to the stage 45 represented in Fig. 2, the annular shoulder 16 begins to upset or swage the open end of the rivet with outward displacement of the metal thereof, and the head 17 of the mandrel continues to upset the closed end of the rivet until finally the tapering 50 portion of the neck 18 is brought against the still cylindrical portion 14 of the rivet as shown in Fig. 3. When this stage is reached, the angular displacement of the mandrel from the axis of the rivet is arrested and the riveting operation is 55 completed, but while the mandrel is gyrating in the angular relation shown in Fig. 3, the neck 18 thereof will expand the still cylindrical portion 14 of the rivet enough to make it quite tight against the wall of the hole in the plates 10 and 11.

60 In addition to its gyroscopic motion about the axis 20 of the rivet, the mandrel may rotate about its individual axis 21, and in so doing it rolls on the rivet without excessive friction and does not become excessively heated or excessively worn. 65 Moreover, during the latter stages of upsetting, the shoulder 16 and the head 17 exert components of force toward the plates to tighten the flange 13 against the outer plate 10 and to tighten the clinched portion of the rivet against the opposite 70 face of the inner plate 11.

To remove the mandrel from a clinched rivet it is only necessary to return the mandrel to coaxial alignment with the rivet and thereupon withdraw the head 17 from the latter. This may

be accomplished by arresting the rotation or gyroscopic action of the mandrel.

In some circumstances, as in aircraft construction, it may be preferable to use countersunk rivets such as that indicated at 14^a in Figs. 4 and 5 to avoid projection of the rivets from the outer surface of the shell thus fabricated. Accordingly, when the holes are bored for the reception of such rivets, they will be countersunk to receive countersunk flanges such as that indicated at 22 in Fig. 4. 10 This procedure will permit the open ends of the rivets to lie in substantially flush relation with the outer surface of the outer plate 10. For operating on rivets of this type, a mandrel such as that shown in Fig. 5 will be used. This mandrel has 15 the same general characteristic as that shown in Figs. 1, 2 and 3 but its form and proportions are modified according to the form and proportions of the rivet to be upset and clinched thereby. Nevertheless, this type of mandrel also comprises 20 an annular upsetting shoulder 16^a, a head 17^a, a tapering neck 18^a and a spherical zone 19^a. The shoulder 16^a is preferably frusto-conical, and even though the internal surface of the open end of the rivet is not initially countersunk, it will finally 25 derive a countersunk formation from the action of the shoulder 16^a as represented in Fig. 5. In all other respects the results produced by this type of mandrel correspond to those produced by the mandrel shown in Figs. 1, 2 and 3.

Having completed the riveting with rivets of the type shown in Figs. 4 and 5, the cavities in the rivets may be filled as shown in Fig. 6 to leave no openings in the outer surface of the fabricated structure. The countersunk formation imparted to the rivet by the upsetting shoulder 16^a provides a seat for a correspondingly shaped flange 23 formed on a metallic plug 24 which is preferably provided at its opposite end with a retaining flange 27 of a diameter that will enable it to pass 40 through the clinched rivet. Before inserting the plug 24, the cavity in the rivet will be partially filled with some suitable plastic retaining material 28 that will harden and provide firm anchorage for the plug which, of course, will be immediately 45 pressed home. The plastic material 28 may be a compound of Celluloid, acetone and aluminum paint.

In situations where greater strength is required than that afforded by aluminum rivets alone, the 50 plates to be riveted may first be secured to each other by lining rivets open at both ends, and when these have been upset and clinched to provide the required strength in the connection of the metal plates 10 and 11, they may be reinforced and closed with supplemental rivets 14^c (Fig. 9) open at one end and closed at the opposite end. This double riveting procedure is illustrated in Figs. 7, 8, 9 and 10 in which a relatively thin lining rivet 25 of stainless steel or 60 other comparatively hard metal is used first to connect the plates 10 and 11 and to provide greater strength than that afforded by rivets made of aluminum. The rivet 25 is initially provided with a flange 26 to be seated against the 65 plate 10, and since a supplemental rivet is to be secured inside this lining rivet, the latter is left open at both ends. The mandrel shown in Figs. 7 and 8 is designed to operate according to the same principles as that shown in Figs. 1, 2 and 70 3 but it differs therefrom in the form and proportions of its characteristic formations which include a frusto-conical upsetting shoulder 16^b, an upsetting head 17^b, a tapering neck 18^b and a spherical zone 19^b. Moreover, the same prin- 75

ciples of operation heretofore described with reference to the mandrels shown in other figures are applicable to the mandrel shown in Fig. 7 to upset and clench the rivet 25 with the result shown in Fig. 8.

When a rivet of this type has been clenched, the opening therein may be closed by inserting a rivet 14^c of softer metal such as aluminum (Fig. 9) and operating on the latter with still another mandrel of corresponding size and proportions comprising a frusto-conical shoulder 16^c, a head 17^c, a tapering neck 18^c and a spherical zone 19^c at the larger end of the neck and adjoining the shoulder 16^c. A mandrel of this type will upset and clench the rivet 14^c with the results pictured in Fig. 10.

It is, of course, possible to accomplish the several riveting operations hereinbefore described by operating the corresponding mandrels manually as by rolling them around the rivets with a gyratory motion while exerting a pressure laterally against their outer ends to apply the force of leverage by which the upsetting of the rivets is effected. Nevertheless, speed of production calls for power-driven mechanism to operate the mandrels, and to this end the invention provides a portable mechanism adapted to be supported manually against the work to be riveted and adapted to utilize high speed of rotation of a power-driven member to operate a riveting mandrel and to apply the above-described force of leverage to the mandrel in consequence of centrifugal force developed by such rotation. A riveting apparatus constructed in accordance with these principles is shown in Figs. 11, 12 and 13.

This apparatus comprises a rigid frame including two parallel bars 30, 30, a nose-piece 31 connecting them, and one or more cross-bars 40 such as that indicated at 32. The bars 30, 30 are provided with grips or handles 33. The nose-piece 31 is provided with a contact plate or disk 34 having a central hole 35 through which the mandrel projects, as shown in Figs. 1, 2 and 3, the outer face of this disk being counterbored to receive the flange of the rivet and to provide a shoulder by which the flange of the rivet may be pressed against the work to be riveted. The cavity thus formed in the disk 34 serves to centralize the nose-piece 31 and the rivet, and also serves to locate the center of the spherical zone of the mandrel at the desired point between the ends of the rivet.

A rotary operating member to be driven at high speed by a power-shaft is journaled in a bearing 36 and comprises a stem or a shaft portion 37, an arcuate head 38 formed thereon and two diametrically opposite lugs 39 formed on the head. The bearing 36 is mounted in the cross-bar 32 to maintain the stem 37 midway between the bars 30, 30 and in coaxial relation to the rivet-receiving hole 35 in the contact plate 34. The stem 37 extends through an axially movable bearing member 40 located between the cross-bar 32 and the head 38, this movable bearing member having grooves engaging the bars 30, 30 by which it is guided to and fro along the stem. The purpose of this to-and-fro movement of the bearing member is hereinafter explained.

The head 38 of the rotary member is provided with arcuate grooves 41, 41 in opposite faces (Fig. 13) and these grooves are occupied by correspondingly curved tongue portions 42, 42 formed on confronting cheeks of a mandrel-carrier 43.

To balance the rotary assemblage so that it

may rotate at high speed without excessive vibration, the head 38 also carries a counterweight 44 which is also provided with tongues similar to the tongues 42 and these tongues are also arranged in the grooves 41.

Referring to Fig. 3, the mandrel-carrier 43 is bored and threaded to receive a threaded bushing 45 which provides a bearing for the shank of a riveting mandrel. The rear end of the mandrel is provided with a head 46 and the bushing 45 is counterbored to provide a socket for this head and is also internally threaded to receive a screw-plug 47 which serves as a thrust bearing for the mandrel and maintains the latter against end-shake. When the parts are assembled, the center of the spherical zone 19 of the mandrel lies on the axis of the rotary operating member comprising the stem 37 and the head 38. Moreover, the axis of curvature of the arcuate grooves 41 intersects the axis of the rotary operating member in coincidence with the center of the spherical zone of the mandrel. Consequently, the axis of the mandrel may coincide with the axis of the stem 37 when the mandrel-carrier occupies its initial position (Fig. 1), but when the mandrel is tilted with respect to the stem 37, its axis intersects that of the stem at the point where the center of the spherical zone of the mandrel lies.

The mandrel-carrier 43 and the counterweight 44 are movable toward and from each other, and the movable bearing member 40 is utilized to equalize their movements, to the end that the rotary mass will remain in balance at all stages of operation. Accordingly, an endless circumferential groove 50 is formed in the bearing member 40 and is occupied by diametrically opposite anti-friction rolls 51 each carried by a pair of bell-crank levers 52. These pairs of bell-crank levers flank the lugs 39 formed on the head 38 and are pressed tightly on pivot-pins 53 that extend through the lugs and have bearings therein. The tips 54 of one pair engage notches 55 in the mandrel-carrier, and the tips of the other pair engage similar notches 56 in the counterweight 44. When the parts are at rest tension springs 57 normally pull the bearing member 40 to the position represented in broken lines in Fig. 11, thereby alining the axis of the mandrel with that of the stem 37, but when the stem is rotated at high speed, as by the shaft 60 of an electric motor, centrifugal force shifts the mandrel-carrier and the counterweight toward the ends of the grooves 41. This force is superior to the opposing force of the springs 57, and the bearing member 40 is ultimately carried by it to the position represented in full lines in Fig. 11.

Since the grooves 41 are curved to produce angular movement of the mandrel the force of leverage is developed to upset and clench the rivets. The several factors involved in the operation of this riveting apparatus are brought about as follows: Rotation of the stem 37 produces centrifugal force; this force, acting on the mandrel-carrier and on the counterweight, is converted into the force of leverage by the curvature of the grooves 41 and applied as such to the mandrel to upset the rivet; the same rotation that generates the centrifugal force to displace the rivet metal radially also produces circumferential progression of the upsetting action about the axis of the rivet; and while all these factors are taking effect the mandrel rotates about its individual axis as it rolls on the rivet. When the driving force is discontinued the mandrel will automatically re-

turn to its initial position in coaxial relation to the stem 37 and may be readily withdrawn from a clenched rivet.

Having thus described our invention, what we claim as new and desire to secure by Letters Patent of the United States is:

1. That improvement in methods of upsetting and clenching hollow rivets of circular cross-section which consists in simultaneously upsetting 10 two diametrically opposite segments of a rivet, one at each end thereof, and extending the circumferential range of such upsetting in both of said segments simultaneously with a common direction of progression about the axis of the rivet.
- 15 2. The improved method defined in claim 1 supplemented by expanding the shank portion of the rivet while the ends of the rivet are being upset as specified.
3. The improved method defined in claim 1 supplemented by applying components of force 20 against the upset segments respectively in opposite directions to press them progressively against the opposite faces of the work as the upsetting of the segments progresses circumferentially.
- 25 4. That improvement in methods of securing rivets in sheet material which consists in executing the method defined in claim 1 first with a rivet open at both ends and thereafter with a rivet closed at one end and extending through 30 the rivet first secured.
- 35 5. That improvement in methods of riveting sheet material which consists in executing the method defined in claim 1 first with a rivet of relatively hard and thin metal open at both ends, and thereafter with a rivet of relatively soft and thick metal closed at one end and extending through 40 the rivet first secured.
- 45 6. That improvement in methods of upsetting and clenching hollow rivets of circular cross-section which consists in inserting a mandrel of circular cross-section into a rivet far enough to place its tip beyond the plane of the work to be riveted, tilting the mandrel against diametrically opposite segments of the rivet and at the same time imparting a gyroscopic motion to the mandrel with movement about the axis of the rivet.
- 50 7. A riveting mandrel having an annular upsetting shoulder, an upsetting head and a tapered neck connecting them, the smaller end of said neck adjoining said head and the largest diameter of said neck being as large as said head.
- 55 8. A riveting mandrel as defined in claim 7 in which the portion of largest diameter of said neck is a spherical zone adjoining said shoulder.
- 60 9. A riveting mandrel as defined in claim 7 in which said upsetting shoulder is tapered and flares outwardly from the larger end of said neck.
- 65 10. A riveting machine comprising a frame structure, a rotary member journaled therein, power-driven means by which said member may be rotated at high speed, a mandrel-carrier, and a riveting mandrel journaled in said carrier to turn about its individual axis, said mandrel-carrier being carried by said rotary member with which it is coupled by arcuate tongue-and-groove connections that constrain the mandrel and its carrier to tilt about a point on the axis of said 70 rotary member and on the individual axis of said mandrel in the rivet-engaging portion of the latter.
- 75 11. A riveting machine as defined in claim 10 in which said tongue-and-groove connections are arranged to permit said mandrel to take one

position in which its individual axis coincides with that of said rotary member.

12. A riveting machine as defined in claim 10 in which said mandrel-carrier is so weighted as to tilt the axis of said mandrel away from alignment with the axis of said rotary member under the influence of centrifugal force generated by rotation about the axis last specified.

13. A riveting machine as defined in claim 10 comprising a counterweight also carried by said 10 rotary member but located diametrically opposite said mandrel-carrier with respect to the axis of said rotary member, said counterweight and said rotary member also having tongue-and-groove connections, and means by which said mandrel-carrier and said counterweight are constrained to move toward and from each other with equal increments of travel to maintain centrifugal balance of the load they impose upon said rotary member.

14. A riveting machine as defined in claim 10 comprising also a work-engaging plate affixed to said frame and having a hole through and beyond which the rivet-engaging portion of said mandrel projects.

15. A riveting machine as defined in claim 10 comprising also a work-engaging plate affixed to said frame and having a hole in concentric relation to the axis of said rotary member, the wall of said hole being formed to surround and engage the flange of a rivet to maintain centered relation of the riveting machine and the work.

16. A riveting machine comprising a frame structure, a rotary member journaled therein, power-driven means by which said member may be rotated at high speed, a mandrel-carrier and a counterweight both carried by said rotary member, a riveting mandrel journaled in said mandrel-carrier to turn about its individual axis, said mandrel-carrier and said counterweight having 40 arcuate tongue-and-groove connections with said rotary member that constrain them to angular movement about a point at once on the axis of said rotary member and on the individual axis of said mandrel in the rivet-engaging portion 45 thereof, means by which said rivet-carrier and said counterweight are constrained to move toward and from each other with equal increments of travel to maintain centrifugal balance of the load they impose upon said rotary member, and 50 resilient means arranged to place said mandrel in coaxial relation to said rotary member in the absence of centrifugal force in opposition thereto.

17. A riveting machine comprising a frame structure, a rotary shaft journaled therein, a 55 bearing member engaging said shaft, movable lengthwise thereof and guided by said frame structure, power-driven means by which said shaft may be rotated at high speed, a mandrel-carrier and a counterweight both carried by said 60 shaft and arranged to maintain balance of centrifugal force due to rotation of said shaft, said shaft having arcuate tongue-and-groove connections with said mandrel-carrier and said counterweight by which both of the latter are constrained to move about a transverse axis intersecting the axis of said shaft, means including 65 said movable bearing member by which the movements of said mandrel-carrier and said counterweight about said transverse axis are 70 equalized, and a riveting mandrel held by said mandrel-carrier and intersected by both of said axes.

GEORGE W. DESHON.

PAUL EMILE MARIE AMANN.
